ELECTRICAL FIXTURE

Ralph Pryne, Pomona, Calif.

Application June 7, 1949, Serial No. 97,519

2 Claims: (Cl. 248—27)

1

This invention relates to improvements in electric lighting or other fixtures and more particularly to improved means for supporting a fixture on joists, beams, frame-work or other parts of a building structure, whereby wall board and/or other surfacing material may be applied in a workmanlike manner. The primary object of this invention is to provide improved hanger means which is simple and inexpensive and by which the fixture can be easily mounted on a vertical, horizontal or inclined wall or other structure. Another object is to provide improved hanger means upon which the fixture can be easily locked in adjusted position without the use of screws, nuts or bolts and which can be readily applied to a fixture. Another object is to eliminate the need of framing for the fixture and to provide means by which the fixture may be of any usual type, whether removable from a wall structure or held permanently therein. Among still further objects is to provide improved hanger means which is applicable to various types of receptacles, whether new or old and whether recessed or mounted on any convenient support.

To these ends my invention comprises the features of construction and combination of parts hereinafter described and claimed.

In the accompanying drawings forming part of this specification, Fig. 1 is a side elevation of a recessed lighting fixture which is shown installed in a ceiling or other wall structure, a portion of the fixture housing and wall structure being broken away and in section and my improved hanger means applied thereto; Fig. 2 is a bottom plan showing the body portion of a lighting fixture fastened to the framework of a wall structure by my improved fastening means prior to the application of button board, wall board and/or other plaster or surface finish, the light bulb and reflector shown in Fig. 1 being removed; Fig. 3 is a plan of one of my improved hanger bars; Fig. 4 is a side or edge elevational view of the hanger bar shown in Fig. 3; Fig. 5 is a plan of a detail illustrating the means by which each of the hanger bars is locked in selected longitudinal position on the supporting frame of the fixture, and Fig. 6 is a section taken on the line 6—6 of Fig. 5, when the hanger bar is locked.

In the drawings, A represents the housing of an electric lighting fixture, it being understood that my improvement is applicable to any type of fixture. One other type of fixture and its housing is disclosed in my companion application, Serial No. 38,234, filed July 12, 1948. The fixture

2

housing is adapted to be installed in a wall structure B, that shown representing a ceiling or side wall. The wall structure shown in Fig. 1 has a button board and building board surfacing or finish 10, but it is to be understood that my improvement is equally applicable to any type of wall structure. The box like housing A is held by its open end in a closely fitting rectangular supporting frame C, said frame assuming a position in the opening 12 which is provided in the wall structure. Screws 13, applied from inside of the housing and its supporting frame C, serve to hold the housing with the edge of its downward open end flush with the outer edge of said frame and even with the outer surface of the wall finish.

The supporting frame or band C is formed with or is secured by welding or other suitable means on the horizontal flange support or plate D, which is adapted to assume a position above or adjacent to the wall finish 10 as shown in Fig. 1. The plate D as shown is rectangular in shape surrounding the fixture housing A and is provided with oppositely disposed pairs of loops 14 and 15 in proximity to the members of each opposite pair of sides of the supporting frame C and the accompanying sides of the housing A. These loops as shown are on the lower side of plate D but they may with substantially equal effectiveness be disposed on the upper side. They are oblong in cross sectional shape and of suitable size to receive and engage an oppositely disposed pair of flat hanger bars or straps E. These hanger bars extend laterally from the housing and are slideable through the loops on the lower side of the supporting plate. The opposite end portions of the hanger bars are adapted to be secured to the lower edges of joists 16 or other members of a building structure in selected longitudinal position by nails 17 or other suitable fastening means which engage through any one of the series of holes 18 in each of the opposite end portions of each bar E. The supporting loops are arranged on opposite sides of the supporting frame C so that a pair of the bars may be applied longitudinally in either selected transverse direction which is most appropriate for positioning the housing and attaching the supporting plate D to members of the wall structure.

In use the bars E are slipped through the loops on each side of a selected pair of sides of the housing supporting frame C and are locked in longitudinally adjusted position either before or after the respective end portions of the bars are secured to a pair of joists or other members of a structure. The bars thus serve to support the

fixture in the wall structure through the wall surfacing 10 which usually is composed of button board and wall board sections or any other type of wall finish.

Locking means is provided for fastening the fixture housing supporting frame C and the supporting bars or straps together in relatively selected longitudinal position. Said locking means consists of a series of teeth or notches 20 in the median portion of one side edge of one or both members of the pair of supporting bars E, and a cooperating tongue or clip 21 which is formed in the plate member D, as shown in Figs. 5 and 6. In use when the fixture housing is positioned longitudinally between the end portions of a pair of bars E, the tongue or clip 21 is bent into engagement with the corresponding members of the teeth or notches, whereby the housing is held and locked on the bars either before or after the latter have been secured to the joists or other supporting members of the wall structure. In this manner no framing is necessary for holding the fixture during or after the application of the wall finish surfacing 10.

It is noted that the broken line position of the joists 16' and hanger bars indicated in Fig. 2, illustrates the application of said bars E' in cooperation with the transverse pairs of loops 14' and 15', on adjacent sides of the supporting frame C, so that the fixture may be placed in either 25 of two transverse directions as desired.

It is further noted that the fixture A as shown in Fig. 1 is provided with a suitable cover 22, but it is to be understood that this feature is not part of the novelty of the present improvement and that the fixture may be of any type to which my improvement is applicable.

For the purpose of defining my improvement the supporting frame C may be considered as an integral part of the fixture housing or a flanged portion thereof, or it may be of any suitable construction for performing its function. Also the type of fixture to which my improved supporting

bars or straps are applied may be of any kind and shape whether used for illuminating or any other purpose within the spirit of the invention.

Modifications are contemplated within the 5 spirit of the invention and the scope of the following claims.

I claim:

1. In a service fixture for installation in an opening in a building structure, a housing supporting marginal collar lining said opening having a lateral supporting flange, a pair of hanger bars secured by their end portions to said building structure, each of said bars having a notched edge between its ends and said flange having loops on its inner surface through which said bars are movably engaged longitudinally, and fastening means on said flange engaging said notched edge for locking said collar in longitudinally selected position.

2. In a fixture for installation in an opening in a building structure, a housing supporting marginal collar lining said opening and having a lateral supporting flange, a pair of hanger bars secured by their end portions to said building structure, each of said bars having a longitudinal toothed edge between its ends and said flange having cooperating engaging means selectively secured longitudinally to said toothed edge for regulating the position assumed by said fixture in said opening.

RALPH PRYNE.
